FIREBOX DOOR

Thomas E. Layden, Topeka, Kans.

Application June 5, 1933, Serial No. 674,368

2 Claims. (Cl. 110—175)

My invention relates to doors for locomotive fireboxes and particularly to the fireboxes of locomotives which burn fuel oil; the principal object of the invention being to provide a firebox door whereby a controllable quantity of air may be admitted, in a prearranged manner, to the firebox in keeping with the operating conditions of the locomotive.

One object of my invention is the provision of a construction whereby the air will be admitted in a plurality of separate streams of relatively high velocity, so as to flow toward the forward end of the firebox and hence penetrate the rising column of vapors and burning fuel to a considerable distance and thus bring about the desired diffusion of air and oil vapor and promote complete combustion in the firebox.

Another object of the invention is the provision of a construction whereby the air may be admitted to the locomotive firebox through the fire door without subjecting the crew in the locomotive cab or persons near the fire door to discomfort caused by drafts of cold air in the cab, or to the hazard of personal injury from fire, steam, or hot water escaping through the opening of the fire door in the event a rivet, flue, stay-bolt or other part of the internal construction of the boiler should become defective or fail and allow steam or hot water from the boiler to be discharged into the firebox.

The above enumerated objects as well as other objects and advantages inherent in the invention will all be readily comprehended from the following detailed description of the accompanying drawing wherein:

Figure 1 is a vertical sectional view of the firebox end of an oil burning locomotive provided with my invention.

Figure 2 is an enlarged vertical sectional view of my improved fire door.

Figure 3 is a cross sectional view taken substantially on the line 3—3 of Figure 2 looking in the direction of the arrows.

As my invention is especially intended for locomotive fireboxes, the firebox end of an oil burning type of locomotive is shown consisting of the usual outside sheet or casing 10, firebox 11, the forward end whereof is provided with the usual flues 12; the firebox and flues being completely submerged or surrounded by water under normal working conditions.

The opening at the bottom of the firebox is enclosed by the usual fire pan 13 which is lined with brick or other suitable refractory material; and disposed transversely of the fire pan and of the firebox is a heavy wall of refractory brick as shown at 14, extending upwardly to approximately the level of the door opening in the firebox, see Figure 1.

The forward end of the fire pan 13 is provided

with an opening 15 through which the oil burner or atomizer 16 projects. The burner or atomizer 16 is arranged centrally in the opening 15 in order that the remainder of the opening may be left clear to admit air for combustion and also to keep the burner from becoming overheated. The burner or atomizer 16 is adapted to provide a jet of finely atomized fuel oil mingled with dry steam; and this jet is projected in the combustion space and against the transverse wall 14 in the form of a spray.

The bottom of the fire pan 13 is provided with an opening 17; while the opposite sides of the fire pan are provided with series of annular openings 18, for the purpose of admitting the major portion of the air required for combustion.

The fire door opening in the rear walls of the firebox and the boiler is formed in a well known manner and the opening surrounded by a suitable frame 19, to which my improved fire door 20 is hingedly connected in the usual manner as shown at 21 in Figure 3.

The fire door 20 is made hollow in construction to permit the passage of air through the interior of the door; and the hollow space 22 inside the door 20 is adapted to be in open communication with the upper end of an air duct 23. The lower end of the fire door 20 or rather the communicating opening at the bottom of the door is preferably made to conform to the shape of the passage through duct 23 and registers with the upper end of this duct when the door is in closed position as shown in Figures 1 and 2.

The duct 23 is rigidly fastened in any suitable manner to the boiler back head so as to provide sufficient clearance between the lower edge of the door 20 and the duct 23, to permit the door to swing on its hinges 21 without interfering with duct 23, while at the same time maintaining a sufficiently close relation between the door 20 and the duct 23 for an uninterrupted air passage.

The duct 23, which preferably is made coextensive with the width and formation of the lower end of the door, extends downwardly through a suitable opening in the locomotive cab floor, a portion whereof is shown at 24; the opening in the floor being such that a snug fitting relation between floor and duct is provided.

The door 20 on its inner face is formed to carry a liner 25 which is adapted to project a considerable distance through the door opening into the firebox. In the particular exemplification the door is shown provided with inturned flanges at 26, along opposite sides, see Figure 3; and the liner 25 along its sides is shown flanged at 27 arranged in lapping relation with the door flanges 26 and thus maintain liner 25 in place.

The liner 25 is in the nature of an open ended

conduit and preferably is internally provided with the vertical and sloping or V-shape partition 28, see Figure 3, whereby a number of nozzle-shaped passages 29 are provided. That is to say, the liner 25 preferably is made to provide two or more nozzle-shaped passages through which air from the interior of the door 20 may pass into the combustion space of the firebox.

The air inlet end of the liner 25 is provided with a damper 30 mounted on a transverse shaft 31, one end whereof is provided with an operating lever 32. The damper 30 is adapted, when in closed position, to cover practically all of the inlet ends of the nozzle passages 29; although in practice the damper 30 is usually arranged to admit a small amount of air when the damper is closed. The purpose of this air admission is to cool liner 25 and prevent the inner or nozzle ends of the liner from burning off.

The lever 32 is rigidly secured to shaft 31 so the latter will rotate and swing the damper 30 from its closed position shown in full lines into an open position as shown in dotted lines in Figure 2. The lever 32 is disposed along a side of the door and the latter is provided with a slotted ear as at 33 to receive a threaded pin on lever 32 which, on the opposite side of ear 33, is provided with a clamping member 34, whereby lever 32 and shaft 31, with damper 30 are held in the desired open position.

The operation of my improved air admitting fire door is as follows:

At low rates of firing, all of the air necessary for proper combustion of fuel oil may be supplied through openings 15, 17 and 18 in the fire pan, which are usually proportioned so that they will supply all of the air necessary for ordinary operation. Under these conditions, the damper is kept in closed position.

However, when the locomotive is working at its maximum capacity, or when the locomotive enters a higher altitude, the amount of air admitted through openings 15, 17 and 18, which was sufficient at low rates of firing, or at low altitudes, becomes insufficient and more air, properly diffused with the vaporized and burning fuel, must be admitted to maintain proper combustion.

It is known to be a fact, that the enlarging of openings 15, 17 and 18, while providing for the admission of greater quantities of air, does not provide for the necessary diffusion of the air with the rapidly vaporizing and burning fuel that is sprayed into the firebox.

Under conditions of maximum firing rates, the column of vaporizing and burning oil spray passes out of the combustion zone adjacent to openings 17 and 18 before vaporization is completed.

It is therefore necessary to admit an auxiliary supply of air higher up in the firebox in order to obtain and realize the proper diffusion of air with the fuel attending or involved in this delayed vaporization. This is accomplished with my improved fire door, through the opening of damper 30, thereby admitting a suitable amount of air through the nozzle openings or passages 29 of the liner 25.

When a locomotive is working at, or near its maximum capacity, a partial vacuum exists in the firebox and this partial vacuum causes the air admitted by my improved fire door to flow through the nozzle openings or passages 29 at a high velocity. By reason of the construction of my improved air introducing means and the ve-

locity of these incoming streams of air, the air streams are caused to flow forwardly and to penetrate to a considerable distance into the rising column of vapors and burning fuel thus inducing and bringing about the desired diffusion of air and oil vapor and hence promoting complete combustion.

It is apparent that with oil burning locomotives as heretofore constructed, while operating under maximum firing conditions, a thorough and complete combustion is not obtained, because the vaporizing and burning oil sprays pass out of the combustion zone at the lower part of the firebox adjacent to the usual air admitting openings. In order to promote proper combustion it is necessary therefore to provide means whereby regulable and controllable quantities of air can be introduced so as to be properly diffused and where it will commingle with and diffuse the rising column of vapors and burning fuel and consequently greatly enhance the efficiency of the locomotive.

The drawing illustrates a simple embodiment of the invention and the exemplification has been described in terms employed merely for purposes of description, as structural modifications are possible and may be made without, however, departing from the spirit of my invention.

What I claim is:

1. In a locomotive firebox, the combination of a hollow fire-door open at the rear to the fire-door opening of the firebox and terminating at the bottom in a downwardly disposed open portion whereby air is admitted into the chamber of the door; a fixedly secured conduit member arranged to register with the lower end of said door portion when the door is closed; an open ended shell member mounted at one end on the rear side of the door so as to extend into the door-opening of the fire-box, the discharge end of said member having a plurality of rearwardly diverging passages arranged side by side and spaced apart, while the other end of the shell member communicates with the air chamber in the door; a damper pivoted in the upper part of the chamber in the door and arranged to extend across the inlet end of the shell; and means extending to the door exterior for manually controlling said damper whereby flow of air from the chamber in the door and through said passages may be regulated.

2. In a locomotive firebox, the combination of a hollow fire-door open at the rear to the fire-door opening of the firebox and terminating at bottom in a downwardly disposed duct portion coextensive with the width of the door whereby air is admitted into the chamber of the door; a fixedly secured conduit member arranged with one of its ends registering with the lower end of said duct portion when the door is closed; an open ended frusto-conical shell member mounted at its large end on the rear side of the door with the other end disposed through the fire-door opening, the shell interior having a vertically extending partition, V-shape in cross section, so as to provide rearwardly diverging passages coextensive with the inner vertical dimensions of the shell; a damper pivoted in the upper part of the chamber in the door and adapted to extend across the upper portion of the inlet end of the shell; an operating lever arranged on the door exterior for controlling the damper; and means carried by the door for locking the lever in its adjusted position.
